APPARATUS FOR REINFORCING CROSSTIES
John A. Fulham, 484 May St., Jacksonville 4, Fla.
Filed Aug. 15, 1961, Ser. No. 131,538
9 Claims. (Cl. 1—302)

This invention relates to railway crossties, their reinforcement with dowel pins and apparatus for reinforcing such crossties without removing the ties from the railway road bed.

A general object is to provide an apparatus for reinforcing crossties of a railway when the ties are in their intrack positions.

Crossties become split and cracked in use and require reinforcing in order to obtain the full useful life from the tie. They are usually reinforced by inserting dowel pins in the ties and in most cases this is done at the ends of the ties because most of the cracks and splits originate thereat and work inward during subsequent use, thereby materially shortening the useful life of the tie.

Some railway companies insert the dowel pins in the new ties as a precautionary preventative maintenance measure whereas others await the origination of the cracks and splits and then reinforce the ties prior to extensive damage thereto.

In the latter case, it is necessary to remove the ties from the road bed, make the necessary repairs and thereafter once again place the ties in the railway road bed. They are removed from the road bed because it has been thought necessary to insert the dowel pins horizontally through the end portions of the tie, and equipment has never been known which could carry out the necessary drilling and ramming operations associated with dowelling a tie, between the adjacent ties while the ties are in their intrack position. This, of course, has led to the costly procedure of removing the tie from the road bed to effect the repairs.

I have found that the cracks and splits can be effectively closed while the ties are in their intrack position and the ties effectively repaired with dowel pins without the need for inserting the dowel pins horizontally through the ties. I accomplish this by inserting the dowel pins diagonally through the tie while the tie is being clamped to close the wood separations. The ties reinforced by the diagonally extending pins are stronger than those previously reinforced because of the ability to use dowel pins of greater length and diameter when desired and because they have a greater resistance to the formation of vertical cracks which develop from the wedging action of the rail splits.

One object of the invention is to provide a new method of reinforcing railway crossties.

Another object is to provide reinforced crossties which utilize dowel pins for their reinforcement.

Another object is to provide an apparatus which is capable of operation on a crosstie in its intrack position to close wood separations in the end portions of the ties, drill the dowel pin holes in the end portion of the tie and press the dowel pins into the holes all in the limited area available in the railway between the rail and the ends of the ties.

Another object is to provide an apparatus which is capable of fulfilling the last mentioned object without regard for the size of the tie and the usual changes in tie spacing in different railways.

Another object is to provide a self-propelled tie dowelling apparatus carriage which eliminates the need for separately mounted dowelling apparatus to accomplish the dowelling operation at both ends of the ties while the latter are in their intrack position.

In accord with certain aspects of the invention, a pair of dowel pins is embedded in each of the ends of the

2

tie to reinforce the tie, the pins being embedded offset from one another and in generally inclined directions in the tie which more or less extend from the opposite upper side edges of the tie toward the lower opposite side edges of the tie. The dowel pins employed are of the usual type employed for dowelling railway ties and may be slightly longer or larger in diameter when desired to take advantage of the greater dimensions encountered in the transverse diagonal directions of the tie.

10 The novel features which are believed to be characteristic of this invention are set forth with particularity in the appended claims. The invention itself, however, both as to its organization and method of operation, together with further objects and advantages thereof, may best be understood by reference to the following description taken in connection with the accompanying drawings, in which:

FIGURE 1 is a top view of the rear portion of a self-propelled railed vehicle embodying concepts of the invention and shows a crosstie dowelling apparatus in working position at one side of a railway, certain parts being broken away to facilitate an understanding of other parts included in the apparatus.

FIGURE 2 is a side view of the crosstie dowelling apparatus as shown in the working position of FIGURE 1 and includes a transverse elevational sectional view through the turntable mechanism thereof generally along the lines 2—2 of FIGURE 1.

FIGURE 3 is a sectional view of the dowelling apparatus generally along the lines 3—3 of FIGURE 1 with certain parts broken away.

FIGURE 4 is a front view of the dowelling apparatus shown in the working position of FIGURE 1 with certain parts broken away and removed to facilitate an understanding of the arrangement of certain parts of the dowel pin ramming mechanism of the apparatus.

FIGURE 5 is a side elevational view of the front portion of the railed vehicle on a diminished scale.

FIGURE 6 is a perspective fragmentary view of a portion of a tie clamping device of the apparatus showing a ballast scooping attachment therefor.

FIGURE 7 is a sectional view along the lines 7—7 of FIGURE 3 illustrating a portion of the means provided for mounting the drills of the dowelling apparatus.

FIGURE 8 is a schematic drawing illustrating the control mechanism for operating the various hydraulically operated components of the dowelling apparatus.

FIGURE 9 is a fragmentary view of certain components used for aligning the rams.

FIGURE 10 is a fragmentary top view of the ram heads in working position.

FIGURE 11 is a fragmentary view of a dowel pin commonly employed for dowelling the ties and which is useful in reinforcing the ties in accord with the invention.

GENERAL

With reference to the drawings, the self-propelled railed vehicle is generally illustrated in the drawings as 1 and carries a crosstie dowelling apparatus designated generally at 2. The dowelling apparatus is mounted on the vehicle by means of a turntable mechanism 3 and includes a horizontally and vertically moveable carriage assembly 4 which is mounted at its rear end on and rotatable with the frame 40 of the turntable mechanism 3. The carriage assembly 4 has a plate frame 6 between the plates 7 and 8 of which is mounted a ballast scooping and tie clamping mechanism 9 and on the forward face of which is mounted components of a drilling mechanism 10. The plate frame 6 in turn supports an auxiliary or secondary carriage 75 at the front end of the assembly 4 that includes another plate frame 11 and on which a

dowel ramming mechanism 12 is mounted. The auxiliary frame 11 is moveable toward and away from the plate frame 6 and carries the control valves 13 for the operation of the various hydraulically operated components of the dowelling apparatus 2.

THE VEHICLE

The vehicle 1 has an elongated generally flat rectangular rigid frame 18 which is horizontally disposed above the rails of the railway and supported on flanged driven wheels 14 at the front end 15 and on flanged rail following wheels 16 at the rear end 17 of the vehicle. The frame 18 includes side forming beam members 19 and 20 which are rigidly interconnected and maintained in parallel by transversely extending cross end members 21 and 22.

As seen in FIGURE 5, the front portion 23 of the frame 18 is elevated above the rear portion 24 and has a diesel motor 25 suitably mounted thereon. Motor 25 is drivingly coupled to a fluid pump 26 that is mounted on a rigid transversely situated plate 27 which is welded to the top flanges of the side forming members 19 and 20. Plate 27 serves as a platform from which the motor 25 and other components of the vehicle drive assembly 28 are controlled.

The front portion 23 of the frame 18 also carries a hydraulic motor 29 between the side members 19 and 20. Motor 29 is driven by pressurized fluid supplied by pump 26 and is drivingly connected to driven wheels 14 through a clutch and transmission mechanism 30. The motor 29 is supported between the members 19 and 20 on an underslung frame 31 which is suspended from the undersides of side members 19 and 20. Frame 31 includes a transversely extending plate 32 which is welded to longitudinally extending channel members that are secured to the undersides of the side members 19 and 20 between the rear portion 24 of the frame 18 and the axle housing 34 for the drive wheels 14, only one of the members, namely member 33, being shown in FIGURE 5.

As best shown in FIGURE 1, the rear portion 24 of the vehicle frame 18 is provided with a pair of transversely extending I beams 35 and 36 which are suitably spaced longitudinally of the vehicle frame 18 for supporting the turntable mechanism 3. Beams 35 and 36 are rigidly connected to the side beams 19 and 20.

THE TURNTABLE MECHANISM

The turntable mechanism is best shown in FIGURES 1 and 2 and includes a solid flat annular track plate member 37. Member 37 is symmetrically positioned on top of transversely extending beams 35 and 36 between the side forming members 19 and 20 of the vehicle and is welded to the cross beams 35 and 36. Annular member 37 is provided with a downwardly and outwardly beveled peripheral upper face portion 38 which functions as track for the rollers 39 on which the frame 40 of the turntable mechanism is mounted and rotatable.

The rollers 39 are tapered to conform to the contour of the track 38 and rest on the beveled portion 38 of the track plate 37. The frame 40 is rotatable about an upright frame retaining assembly 41 which is disposed axially within the annular portion 42 of the plate member 37. The retaining assembly 41 prevents horizontal radial movement of the frame 40 relative to the track plate 37 and includes a hollow sleeve 43 which is provided with a radially extending lower flange portion 44 and a center pin element 45. The flange portion 44 of sleeve 43 is rigidly mounted on a rest plate 46 that is securely fixed on top of and extends between cross beams 35 and 36 within the annular portion 42 of the track plate 37 with the sleeve portion upright. Pin 45 snugly fits within the fixed sleeve 43 and the stem 47 of the pin 45 passes through a suitable opening 48 in the rest plate 46, thence downwardly between the cross beams 35 and 36, and is secured beneath the cross beams

5 by a nut 49 which threadedly engages the stem 47 and bears upwardly against another plate 50 through which the stem passes. Plate 50 extends transversely across the space 51 and between beams 35 and 36 and is welded to the bottom flanges of the beams.

10 The rigid turntable frame 40 is provided with a centering sleeve 52 which is rotatable with the frame 40 and which snugly surrounds the fixed sleeve 43 of the retaining assembly above flange 44. The top of frame sleeve 52 is disposed spacedly below the head 53 of center pin 47 so as to permit a small cylindrical thrust bearing 54 to be interpositioned between the center pin head 53 and the upper end of the sleeve 52. Bearing 54 absorbs any upward thrust from the frame 40 caused during the working of the mechanisms of the dowelling apparatus.

15 The load bearing components of the flat horizontally disposed turntable frame 40 include a rigid square inner frame portion 55 and a rigid square outer frame portion 56 which are aligned symmetrically one within the other and in symmetrically axial alignment with and radially outwardly of sleeve element 52. The opposite and parallel end forming members 57 and 58 of the inner frame portion 55 have integral extensions 59 at their opposite ends which are rigidly secured to the opposite and parallel side forming members 60 and 61 of the outer frame portion 56 thereby rigidly connecting the respective portions with the adjacent side and end members of the frame portions in parallel, as illustrated by end member 57 of the inner frame portion 55 and parallel end member 62 of the outer frame portion 56.

20 As best illustrated in FIGURES 1 and 2, sleeve 52 is joined to the framing members of the inner frame 55 by means of radially extending bars 63 which link and are fixed to the sleeve 52, and to the insides of the corners 64 of the square inner frame portion 55 as by welding.

25 Each of the side and end forming members of the outer frame portion 56 are disposed above and offset outwardly of the track 38 as shown by end member 62 in FIGURE 2. The middle portions of the adjacent parallel side or end forming members of the inner frame portion 55 are offset inwardly of the track as illustrated by end member 57. This enables the mounting of four rollers 39 between the inner and outer frame portions. Thus, 30 roller 65 is mounted midway between the ends of the adjacent parallel members 57 and 62 of the inner and outer portions of the frame and the other three frame supporting rollers are similarly mounted.

35 Outwardly of and in axial alignment with the flat circular track plate 37 is an annular turntable track gear 66 which is carried by the turntable frame 40. The gear is slung beneath the outer frame portion of the turntable frame and is secured to each of the side and end members of the outer frame, as illustrated by reference to end member 62. As shown, spacer blocks, such as block 67, are welded on the bottom flanges such as flange 68 of end member 62 and the gear is welded to the bottom of the blocks.

40 As shown in FIGURE 1, a fluid motor 69 is mounted on the rear face of a cross beam 70 of the vehicle frame. Beam 70 extends between and is connected to side members 19 and 20 of the vehicle and is suitably disposed forwardly of the turntable gear. The motor 70 has an attached gear mechanism 71 that includes a pinion 72 which is driven by the motor. Pinion 72 is horizontally aligned with and drivingly engages the gear 66 to rotate the turntable frame 40 on the track plate 37.

THE CARRIAGE ASSEMBLY

45 The carriage assembly 4 includes a horizontally moveable carriage frame 73 at the rear of the assembly 4 which is mounted on the turntable frame 40 and a vertically moveable carriage 74 which is suspended from the front end of frame 73. Carriage 74 has a narrow upright plate frame 6 which is adapted for transverse placement on

a cross tie and on which is mounted an auxiliary carriage 75 that is designed for movement of the ramming mechanism 12 into operative position for pressing the dowel pins into the ties.

The horizontal carriage frame 73 is a generally elongated flat horizontally disposed structure that carries the rail guides 64 and 65 for the vertical carriage 74 and is suspended on rollers 76 between a pair of horizontal rail guides 85 and 86 that are rigidly mounted on the upper face 78 of the turntable frame 40.

As seen in FIGURES 1 and 4 the rail guides 85 and 86 are elongated U-shaped channel members which are arranged atop the turntable frame 40 in horizontal parallel spaced relationship with their flanges 79 extending inwardly of the side members 69 and 61 of the turntable frame 40. Each of the rail guides 85 and 86 is disposed above and offset inwardly of a respective side member of the outer frame portion 56 of the turntable frame 40 and spans the top of the frame transversely of the lateral extensions 59 of end members 57 and 58 of the inner frame portion 55 thereof. The rail guides 85 and 86 extend outwardly of and above the respective end members 62 and 63 of the turntable frame and terminate inwardly of the side extremities of the vehicle when the turntable is in the position shown in FIGURE 1.

The rail guides 85 and 86 are joined and braced at the rear ends of the guide components by an interconnecting rigid end plate 82 which joins the guides and is welded to the respective components 85 and 86. Plate 82 is provided with a pair of inwardly extending ears 83, intermediate its ends for mounting the horizontal carriage cylinder 84 of the carriage assembly. The cylinder 84 is positioned between the respective rail guides 85 and 86 with the piston arm end extending inwardly of end plate 82 and has an eye component 103 at one end which is disposed between the ears 83 and connected thereto by pivot pin 104.

Slung beneath the overhanging rear end portion 87 of the rail guides 85 and 86 is a counter weight 88 which is designed to balance the weight of the apparatus carried at the front end of the carriage frame 73. Counter weight 88 is affixed to the rail guides 85 and 86 and is disposed outwardly of end member 63 of the turntable frame 40 and above the ring gear 66 so as not to interfere with the movement of the turntable mechanism.

The guides have a front portion which extends forwardly of the turntable frame 40. However, the front ends of the rail guides are open so as to accommodate the movement of the horizontal carriage frame 73.

The carriage frame 73 includes a pair of solid side forming bar members 90 and 91 which are maintained in parallel at their front ends by a suitable interconnecting brace 92 that extends transversely between and is suitably welded to the inside faces of the rails 90 and 91. Brace 92 is offset rearwardly of the vertical rail guides 64 and 65 which are carried at the front of the horizontal carriage frame so as to accommodate the connection of the vertical guides 64 and 65 to the front ends 94 and 95 of horizontal rails 90 and 91, and to enable the guides to be tilted toward the horizontal carriage when desired.

In addition to brace 92, the rails 90 and 91 of the carriage frame 73 are also braced by another interconnecting carriage frame member 96. Brace 96 interconnects and is welded to the rails 90 and 91 forwardly of their rear ends, 97 and 98, and is positioned sufficiently forwardly of the rail ends to accommodate the disposition of the carriage cylinder 84 between the brace member 96 and the guide connecting end plate 82 when the carriage frame 73 is fully drawn into the rail guides. Member 96 is provided with a pair of ears 99 on its rear face, as shown in FIGURE 1, for connecting the end eye component of the piston arm 100 of the cylinder 84 to the carriage frame 73. This is accomplished by means of a pivot pin 101 which passes through the ears 99 and through the intervening eye component 102.

Each of the rails 90 and 91 is disposed in parallel juxtaposition to the flanges 79 of one of the rail guides 85 and 86 and is provided with a pair of rollers 76 which are carried on the outside of the rail between the flanges of the adjacent rail guide. The rollers are suitably spaced longitudinally of the rail to support the frame between the guides as the carriage frame is moved back and forth by cylinder 84. The rollers 76 bearingly cooperate with the flanges 79 in supporting the load of the carriage and its associated apparatus, and the upper flanges of the guides prevent the carriage frame 73 from tilting under the load supported thereon.

The rails of the carriage are of sufficient length to facilitate the proper placement and working of the various components of dowelling apparatus 2 hereinafter described.

The vertically moveable carriage component 74 of the carriage assembly 4 is pivotally mounted at the front end of the horizontal carriage frame 73 and is retained in an upright position by a pair of adjustable turnbuckle mechanisms 115 and 116 which are mounted in the horizontal carriage frame and connect with the vertical carriage guide components 64 and 65.

The carriage guide components 64 and 65 of the assembly 4 are U-shaped channels, which are pivotally connected to the front ends of the horizontal rails 90 and 91 with the flanges 105 of the channels extending inwardly of the rails in a manner similar to the rail guides 85 and 86 of the horizontal carriage frame 73. As shown in FIGURES 1 and 2, vertical rail guide 64 is connected to rail 90 of the horizontal carriage frame 73 by means of a pivot pin 106 which passes through the end 94 of rail 90 and through the flange interconnecting web of the guide 64. Guide rail forming channel 65 is similarly connected by means of pivot pin 108, and the respective channels are maintained in parallel by means of transversely extending top and bottom cross braces 109 (FIGURES 2 and 3) and 110 (FIGURE 1) which are affixed to the guides.

Brace 109 is a flat plate which extends transversely of and between the guide rails 64 and 65 and is secured at the top of the rails as by welding, to the front flanges 111 of the respective guides 64 and 65. Brace 109 is provided with a pair of horizontally spaced and forwardly extending ears 112 for purposes of mounting the vertical cylinder 113.

The lower portions of the guides 64 and 65 extend downwardly from their pivotally connections with the horizontal carriage and are interconnected by a transversely extending brace 110 which is arranged between the rear flanges of the guides and secured to the flanges by welding.

The guides 64 and 65 are maintained in the vertical position shown in FIGURE 2 when the dowelling apparatus is being employed by means of the turnbuckle mechanisms 115 and 116 previously referred to.

To facilitate the mounting of the turnbuckle mechanisms on the horizontal carriage frame, and to further brace the rails in spaced relationship, the frame 73 is provided with a transversely extending flat cross brace 117 that is disposed on top of the rails 90 and 91 spaced rearwardly of the vertical rail guides 64 and 65. A pair of upstanding ears 118 is provided at each end of the cross brace 117 and is welded to the brace for attaching the turnbuckle mechanisms 115 and 116 to the horizontal carriage frame 73.

The elongate turnbuckle mechanisms 115 and 116 as illustrated in FIGURE 2 by reference to mechanism 115, are pivotally connected at their lower ends by means of a pivot pin 119 which passes through the lower end of the mechanism and through the ears 118 that are mounted on the brace 117. The mechanisms 115 and 116 extend forwardly of their carriage connections inclined upwardly and at the upper ends are connected to the vertical rail guides, such as guide 64 by means of another pin 120 which passes through the end of the mechanism and a

rearwardly extending lug 121 that is welded to the rear flange of the rail at a point roughly intermediate to the upper end of the rail and its pivotal connection with the horizontal carriage rail.

The drilling and tie clamping mechanisms 9 and 10 are mounted on a rigid narrow upright frame portion 6 of the vertical carriage 74 as is the auxiliary carriage assembly 75 on which the ramming mechanism 12 is mounted. The frame 6 is adapted to be arranged transversely of the tie 122 to be dowelled and to rest upon the upper face of the tie between the tie end 124 and the rail plate 125 as shown in FIGURE 2. It is sufficiently narrow to accommodate the working of the drilling and ramming mechanisms outwardly of the front plate 7 of the frame 6 when thus arranged.

The frame 6 includes, in addition to the front upright plate member 7, a correspondingly similar upright rear plate 8 which is spaced rearwardly of and disposed in parallel to the front plate 7. The frame is provided with a small rest plate 126 at the bottom which extends between the plates of the frame and is affixed to the bottom edges of the respective plates 7 and 8 intermediate the lower side edge portions 127 and 128 of the frame. Plate 126 is adapted to rest on the upper face of the tie 122 when the drilling and ramming mechanisms are being operated and is of sufficient size as to not interfere with the operation of the depending arms of the clamping mechanism that are disposed outwardly thereof and adapted to engage the opposite sides of the plate 126.

The upright frame 6 is disposed generally offset forwardly of and in parallel with the general plane of the rail guides 64 and 65 for the carriage 74 and the lower portion 129 of the frame extends laterally of the rail guides toward the sides of the carriage assembly 4. Each of the opposite lower lateral extensions 130 and 131 of the frame 6 are provided with a transversely extending open ended sleeve as illustrated by sleeves 132 and 133, which is affixed to and passes through the front and back plates 7 and 8 of the frame 6. In each of the sleeves 132 and 133 is rigidly mounted a forwardly extending solid shaft component of the auxiliary carriage 75, as illustrated by parallel horizontal shafts 134 and 135.

Above the lateral extensions 130 and 131 the sides 137 and 138 of the frame 6 taper upwardly and inwardly to the open top portion 138 of the frame 6. Portion 138 is generally disposed forwardly of and between rail guides 64 and 65 as shown in FIGURE 4. The tapered side portions 143 and 144 are open between the plates 7 and 8 to accommodate the mounting and working of certain components of the drilling mechanism 10 as described hereinafter.

The upper portion 145 of the frame 6 is provided with a pair of plate spacing upright and parallel frame and rail reinforcing gusset plates 139 and 140 which connect and extend downwardly between the back and front plates 7 and 8, of the frame 6. The gusset plates are arranged at opposite sides of the open top portion 138 of the frame 6, and terminate spacedly below the top edges of the plates 7 and 8 a suitable distance. Each of the gusset plates is rigidly connected to the front and back plates 7 and 8 of the frame 6 and is provided with an upper extension, such as extensions 141 and 142, which projects above the plates 7 and 8. These extensions 141 and 142 are respectively aligned with the adjacent front flanges 146 of the upright and parallel vertical rails 147 and 148 and are welded thereto.

The rails 147 and 148 are L-shaped channel members which are mounted upright and in parallel against the back of plate 8 with one of their flanges 146 extending inwardly toward the other rail and with the other flange 150 extending rearwardly of the back plate between the rail guides 64 and 65. As shown in FIGURE 1, the respective rearwardly extending flanges 150 of the rails 147 and 148 are disposed adjacent to a respective rail guide 64 and 65 and carries a pair (FIGURE 2) of suitably

spaced rollers 151 which are rotatably mounted on the guide side of the rail flange between the flanges 195 of the guide rail, whereby the carriage is restrained in its horizontal movement relative to the rail guides.

5 The plate frame 6 is suspended from the upper cross brace 109 for the rail guides 64 and 65 by means of depending vertical carriage cylinder 113 which is connected to the brace 109 by means of a pivot pin 152 which extends through ears 112 and the eye component 153 that is secured to the upper end of the cylinder. Cylinder 113 is disposed intermediate the sides 136 and 137 of the frame 6 and generally above the frame. The piston arm 154 is pivotally connected to the frame 6 through a small elongated horizontally disposed plate 155 which is welded to the front and rear plates 7 and 8 of the frame 6 beneath the open top portion 138 of the frame, about midway between the top and the bottom of the frame. Plate 155 is provided with a pair of affixed upstanding spaced ears 156 and the connection is made with the piston arm 154 by means of a pivot pin 158 which passes through the ears 156 and through the intervening eye component 157 of the piston arm as shown in FIGURE 2. The gusset plates 139 and 140 are suitably spaced laterally of the cylinder to enable passage of the piston arm 154 of the cylinder through the opening between the plates 7 and 8 to permit also the passage of the lower end of the cylinder between the plates when the carriage is fully drawn up in rail guides.

20 The auxiliary frame 11 is slidably mounted on the parallel shafts 134 and 135. The shafts are of sufficient length to enable the movement of the frame 11 toward and away from frame 6, to accommodate the working of the drilling mechanisms between the respective frames. The shafts are joined at their outer ends by a transversely extending cross plate 159 which is welded to the ends and on which is mounted a bracket 160 to which the operator's seat 161 is pivotally connected.

25 The auxiliary frame 11 of the auxiliary carriage assembly 75 includes a pair of elongated transversely extending upright plate members 162 and 163 which are spaced at the bottom of the frame 11 by a pair of fixed sleeves 164 and 165 which are welded to the plates 162 and 163 in axial alignment with the respective frame supporting shafts 134 and 135. The sleeves 164 and 165 of the frame 11 are slidable on the respective shafts 134 and 135 to enable the frame to be moved back and forth on the shafts.

30 The bottom of the frame 11 is open and the lower edges of the plates 162 and 163 are in the same horizontal plane as the bottom edges of the plate members 7 and 8 of head frame 6. The plates 162 and 163 are spaced at the top by a transversely extending control deck 166 which is fixed to the parallel plates 162 and 163 at the top of the frame, as shown in FIGURE 2. The deck projects slightly outwardly of the front face 167 of the frame 11.

35 The auxiliary frame 11 and plate frame 6 are interconnected by a hydraulic cylinder 168 which is adapted to move the frame 11 back and forth on shafts 134 and 135 to move the ramming mechanism out of and into working position. The cylinder 168 is pivotally connected at one end as at 169 (FIGURE 3) to the inside face of plate 8 immediately above rest plate 126. It extends forwardly of the pivotal connection 169 through a suitable opening 172 in plate 7 and the piston arm 171 of the cylinder is pivotally connected to the inside face of plate 162 of the auxiliary frame 11, as at 170. Another suitable opening 174 is provided in the rear plate 163 of the auxiliary frame 11 to accommodate the arm as well as the portion of the cylinder which extends forwardly of plate 7 when the arm 171 is retracted and plate 163 is drawn into close proximity with plate 7.

40 The auxiliary frame 11 is also provided with a horizontally disposed foot rest 175 which is mounted on the outer face 167 of plate 162 beneath the shafts 134 and

135. The shafts extend over the foot rest 175 when the auxiliary frame 11 is drawn rearwardly toward plate frame 6.

As shown in FIGURE 2, the seat 161 is mounted forwardly of frame 11 on a pair of elongated equal length parallelly outwardly and upwardly inclined seat supporting members 176 and 177. These members are pivotally connected, as at 179 and 180, at their lower ends to the bracket 160 that is mounted on member 159 intermediate shafts 134 and 135. The upper ends of the members 176 and 177 are pivotally connected to the seat as at 181 and 182. One end of a frame linking arm 178 is pivotally joined as at 181, to member 176 intermediate its ends. The other end of the link 178 is pivotally connected, as at 182, to the face of the plate. Member 177 is spaced outwardly of member 176 and it is deemed apparent that the seat 161 pivots upwardly and rearwardly as shown by dotted lines 183 as the frame 11 is drawn toward frame 6 by cylinder 168. As such when the auxiliary frame 11 moves rearward on shafts 134 and 135, the seat 161 is caused to pivot on its mounting and move rearwardly and upwardly, being maintained, however, in parallel by reason of the two arm connections employed. This enables the operator to more closely observe the ramming action of the ramming mechanism through the observation holes 184 provided in the front plate member 162 of frame 11, the holes 184 being best shown in FIGURE 4.

THE CLAMPING MECHANISM

The clamping mechanism includes a pair of elongated jaw carrying arms 185 and 186 which are pivotally mounted between the plates 7 and 8 of frame 6 by transversely extending pivot pins 191 and 192. Pins 191 and 192 are mounted at their opposite ends in plates 7 and 8.

The arms 185 and 186 are pivoted generally intermediate their opposite ends and have lower jaw carrying portions 187 and 188 which depend beneath the frame 6 adjacent to the opposite sides of the rest plate 126 and which are adapted and arranged to straddle the tie 122 to be dowelled on opposite sides 189 and 190 thereof.

The upper portions 193 and 194 of the arms are joined through a floating horizontally disposed hydraulic cylinder 197 and are pivotally connected to the opposite ends of the cylinder 197, as by pivot pins 195 and 192, the cylinder 197 being disposed in the frame between auxiliary carriage cylinder 168 and plate 155. The action of the mechanism is such that when the piston arm 202 is extended, the upper portions of the arms are caused to move toward the sides of the frame and the lower jaw carrying portions 187 and 188 of the respective arms 185 and 186 swing inwardly on their pivotal connections and engage the opposite sides of the tie with a vise-like grip as shown in FIGURE 3.

As seen in FIGURE 6, with reference to arm 186, the lower portion 188 of the arm is offset forwardly of the upper portion 194 to enable the jaw to be disposed closer to the portion of the tie to be dowelled so as to insure the closure of the cracks and splits in the tie portion 122. Both jaw carrying arms are similar in this respect.

The jaws 200 and 201 are pivotally mounted at the respective lower ends of the arms 185 and 186 by pivot pins 198 and 199 so as to be self-aligning with the contour of the tie sides and are maintained in general vertical alignment with the sides 189 and 190 of the tie 122 by means of tension springs such as spring 203. As seen in FIGURE 6, the spring 203 is connected adjacent the upper side of the jaw plate in the position shown and extends outwardly and upwardly thereof to its connection with the arm portion 188 and thus, maintains the jaw plate generally in vertical alignment with the side of the tie.

A scooping attachment 205 is provided on each jaw, which as illustrated with reference to the jaw 200 in FIGURE 6, is mounted on the forward edge 206 of the

jaw plate 204 by screws 207. The attachment has a tie engaging flange 208 through which clamping pressure is applied forwardly of the jaw plate. The attachment also has a flange portion 209 which extends rearwardly of the jaw plate 204 and which functions as a ballast scoop. For example, when the jaws are positioned to straddle a tie and the vertical carriage cylinder is extended, the jaws are forced into the road bed ballast. Thereafter by extending the arm of the horizontal carriage cylinder, the carriage assembly and the jaws are moved toward the end of the tie. During this movement, flange 209 of attachment 205 shoves the ballast outwardly of the end of the tie to clear the tie for clamping engagement by the jaw. Flange 208 also serves to scoop ballast away from the sides of the tie when the jaws have been driven downwardly into the ballast and the piston arm 202 is retracted, thus forcing the jaws laterally of the sides of the tie. It should also be noted that the attachment 205 projects below the bottom edge of the jaw plate 204 to facilitate the scooping action of the respective flanges of the attachment.

The floating cylinder arrangement enables the arms to adjust themselves to the tie when the frame 6 is placed on the tie in slight misalignment therewith.

THE DRILLING MECHANISM

The drilling mechanism 10 is composed of a pair of drill assemblies which may be simultaneously or selectively operated to drill diagonally extending holes adjacent the end of the cross tie and which are designated as 210 and 211 in the drawings. The drills 212 and 255 of the respective assemblies incline downwardly and inwardly toward the respective adjacent top side edges 217 and 256 of the tie from the opposite sides of the carriage assembly 4 and have axes which are generally perpendicular to the tie and offset longitudinally thereof so as to enable the drilling of inclined, and preferably substantially diagonally extending, offset holes 215 and 257 in the tie as illustrated in FIGURE 3. The drilling components of the respective assemblies are mounted on the front plate 7 of the head frame 6 and are swingably mounted in parallel with the plate 6 into and out of their respective working positions, depicted in FIGURE 3, by means of hydraulic cylinders 240 and 241. These cylinders are mounted between the plates 7 and 8 of the head frame 6. But for minor differences mainly pertaining to the offset nature of the drills, the assemblies 210 and 211 are substantially identical and symmetrically mounted to work at opposite sides of the tie and accordingly will be described most particularly with respect to assembly 211.

The assembly 211 includes a drill 212 composed of a fluid motor 213 and a twist drill 214. The drill is swingably mounted on the front plate 7 and is adjustably arranged and adapted to assume a working position, as shown in FIGURE 3, such that its axis extends in a direction which is inclined downwardly and inwardly toward the tie to thereby enable the drilling of a hole 215 in the end portion 216 of the tie 122 that extends preferably in a direction which is generally diagonally from the top side edge 217 of the tie 122, adjacent to the assembly 211, to the opposite bottom side edge 218 of the tie. The motor 213 is mounted on the back side of a bracket 219 which is slidably mounted on an elongated inwardly and downwardly inclined straight bar 220 which is square in cross section as shown in FIGURE 7. The bar is carried on the frame 6 outwardly of and in front of the face 167 of the frame plate 7 by means of a swinging arm 233 and swinging yoke type member 239. The drill is disposed rearwardly of the bar 220, between the bar and the plate 7 and is offset forwardly of the latter. Its axis is parallel to the bar 220. The movement of the drill 212 on the bar 220 is controlled through actuation of a hydraulic drill feed cylinder 221 which is slung beneath the upper end of the bar with its working axis also in parallel with the bar. A similar drill feed cylinder 221'

is provided for drill 255 of assembly 210. The outer end 222 of the bar 220 is provided with a pair of depending ears 223 by means of which the outer end of the cylinder is attached by a pivot pin 224 to the bar 220. The piston arm 225 of the cylinder 221 is pivotally secured to the bracket 219 by means of a pivot pin 226 which passes through the end of the piston arm 225 and through a pair of depending ears 227 that are affixed to the bottom of the slidable bracket 219. When the piston arm 225 is extended, the drill 212 is forced downwardly on the bar 220 and the tool end 214 of the drill is forced into the tie 122 and conversely, when the arm 225 is retracted the drill is drawn upwardly on the bar to the position shown in FIGURE 3 with the drill out of tie engagement.

The bar 220 is connected to arm 233 through an L-shaped elongated shoe 228 which opens downwardly and inwardly and is arranged as shown in FIGURES 2 and 3 to fit over the adjacent side edge 217 of the tie. The lower end 229 of the bar 220 is welded to the front end 230 of the shoe 228 and the rear end 231 of the shoe 228 is disposed spacedly rearwardly thereof and adjacent to the front plate 7 of the frame 6. This end 231 of the shoe 228 is pivotally connected as at 232 to the depending swingable arm 233 of the assembly. The arm 233 extends upwardly from its pivotal connection 232 with shoe 228, is offset from the face 167 of plate 7 and is pivotally connected as at 234 to the depending piston arm 235 of a shoe adjusting hydraulic cylinder 236. Cylinder 236 is mounted adjacent to the top of the frame and on the face 167 of the plate 7 as shown in FIGURE 2. Arm 233 is adapted to swing from the piston arm 235 in parallel with the front face 167 of the plate 7. The cylinder 236 is pivotally connected at the top of the plate 7 to a pair of forwardly extending ears 237 which are welded on the face 167 of the plate intermediate the sides of the frame and adjacent to the top of the frame 6 as shown in FIGURE 3.

The shoe 228 is provided with an opening 238 between its opposite ends 230 and 231 and the opening is aligned with the axis of the drill 212. The shoe opening 238 serves as a guide for the twist drill 214 when the latter is forced into the tie to drill the dowel hole 215.

The upper end 222 of the bar 220 is mounted on the frame 6 by a yoke type swingably mounted member 239 that is pivotally connected to the hydraulic cylinder 241 which is mounted between the plates 7 and 8. The plates 7 and 8 are provided with opposite tapered upper side edge portions 143 and 144 to accommodate the connections with the respective cylinders 240 and 241 of the assemblies 210 and 211 as shown in FIGURE 3. Member 239 is provided with a pair of elongated downwardly and outwardly inclined arm elements 242 and 243 which are offset from each other as shown in FIGURE 1 and are connected by an integrally formed link 244. From the ends 245 and 246 of the link, elements 242 and 243 extend in parallel opposite directions. Element 242 extends upwardly and inwardly of end 246 of the link 244 and is disposed adjacent to the front plate 7 of the frame. The upper end of element 242 is pivotally connected on the front face of the plate adjacent the top corner 247 of the frame by a pivot pin 248. Element 243 inclines downwardly and outwardly of the forward end 245 of link 244 above the bar 220 and is pivotally connected to the bar. This connection is made by a pivot pin 249 which passes through the outer end of the element 243 and a pair of upstanding ears 250 that are welded to the top side of the bar 220 between the end of the bar and the innermost position of the bracket when the piston arm of cylinder 221 is fully retracted.

The link 244 is provided with an integrally formed rearward extension 251 which passes over the tapering upper side edge of the plate 7 and which is pivotally connected to cylinder 241 by pivot pin 252. Cylinder 241 is mounted between the plates 7 and 8 of the head frame

by means of a pivot pin 253 which extends between the plates and passes through an eye element at the lower end of the cylinder 241. Cylinder 241 inclines slightly inwardly from the vertical as shown in FIGURE 3 and the piston arm end of the cylinder 241 is connected to the rear end of link extension 251 by means of pivot pin 252 which connects the end of the piston arm with a pair of depending ears 254 that are formed integral with the extension 251.

10 Cylinders 236 and 241 provide an adjustable means for positioning the shoe 228 at the side edge of the tie and accordingly for positioning the drill in a working position with its axis inclined downwardly and inwardly toward the adjacent top side edge of the tie. This arrangement permits the drilling mechanism to be employed for drilling ties which vary in sizes from one railway to another.

As shown in FIGURES 1 and 3, the drills 255 and 212 of the assemblies 210 and 211 are offset from one another and have working positions on opposite sides of the tie. Drill 255 is offset forwardly of the drill 212, so as to enable the drilling of dowel pin holes 215 and 257 which are adjacent and offset from one another and which incline downwardly from the opposite upper side edges of the tie 122. Drill 212 is disposed slightly closer to the face 167 of frame plate 7 than drill 255. This offset arrangement is accomplished in the embodiment by interposing a small block 258 between the bracket 219 and the mounting plate for motor 213 of drill 212 as shown in FIGURE 7, whereas a block is not used in mounting drill 255. The hole 259 in shoe 260 of assembly 210 is, of course, similarly offset forwardly to enable the twist drill of drill 255 to register therewith.

35 Shoe adjusting cylinder 236 is common to both assemblies 210 and 211 and the arm 261 of assembly 210 is pivotally connected to the piston arm 235 of the cylinder by the same pin 234 used for connecting arm 233 thereto. The arm 261, however, is disposed on the opposite side of the eye component of the piston arm 235 as shown in FIGURE 2. Arm 261, as such, is disposed closer to plate 7 than arm 233 and, of course, the lower end pivotal connection 262 between the arm 261 and shoe 260 is similarly offset.

40 The drills 255 and 212, as shown in FIGURE 3, are positioned in their respective working positions on opposite sides of the tie. By causing the piston arms of cylinders 240 and 241 to become extended the drills 255 and 212 of the assemblies can be swung outwardly from their working position to remote positions generally above and in front of the tapered side portions of the frame 6, as exemplified with respect to assembly 210 by the dotted line position 263. Thus, although the drills 255 and 212 are mounted on the front plate 7 and perform their function adjacent thereto, they are capable of being swung out of their working positions to remote positions to enable the ramming mechanism carrying auxiliary plate frame 11 to be drawn into a position generally beneath the drills so that the rams can be disposed in working positions to press the dowel pins in the drilled holes.

45 It is deemed evident that the degree of inclination of the dowel pin holes drilled by the drills 255 and 212 is determined by the positions which the drills assume with respect to the tie when the guide shoes are placed on the opposite side edges thereof. As such, whether the holes are truly diagonal or not, in the sense that they respectively extend from the opposite upper side edges of the tie to the opposite lower side edges, is a matter determined primarily by the rectangular cross sectional dimensions of the particular tie being dowelled and the 50 working positions assumed by the drills. However, it is evident that the holes extend in directions which are oppositely inclined and substantially diagonal.

THE RAMMING MECHANISM

55 The ramming mechanism 12 is best illustrated in FIG-

URES 4, 9, and 10 and is composed of a pair of ram assemblies 264 and 265 and includes oppositely mounted rams 266 and 267 and ram alignment devices 268 and 269.

The rams are pivotally mounted between the plates 162 and 163 of the auxiliary frame 11 toward the opposite sides of the frame and are each arranged to press a dowel pin in one of the diagonal holes 215 and 257 drilled by the drills 212 and 255 of the drilling mechanism. As such, the axes of the rams 266 and 267 are maintained by the alignment devices to converge downwardly and inwardly of the opposite sides 270 and 271 of the frame and generally in parallel with the respective axes of the corresponding drills 255 and 212 when the latter are in their working positions as shown in FIGURE 3. The outer ends 272 and 273 of the rams 266 and 267 project outwardly through the open sides 270 and 271 of the frame 11. The rams 266 and 267 are so arranged in the frame 11 that when their piston arms 274 and 275 are fully retracted and the ram mechanism is in working position that the heads 276 and 277 of the rams are sufficiently spaced from the adjacent side edges 256 and 217 of the tie 122 to enable the operator to position dowel pins between the ram heads and the holes 215 and 257 in which the pins are to be pressed. The pins are interposed between the ram heads and the ties manually through the openings 184 provided in front plate 162 (FIGURE 4).

The assemblies 264 and 265 are substantially identical except that one operates on one side of the tie whereas the other operates on the other side of the tie, and accordingly, the respective assembly will be described most particularly with reference to assembly 265, it being deemed apparent that assembly 264 is different only to the extent that it is symmetrically mounted to work from the opposite side of the tie from assembly 265.

Ram assembly 265 includes hydraulic ram cylinder 267 and an alignment device 269. The cylinder is pivotally connected to the frame 11 adjacent to the piston arm end of the cylinder and is carried between plates 163 and 162 of frame 11 on axially aligned and oppositely extending pivot pins 279 and 280 (FIGURE 2). Pins 279 and 280 are mounted on opposite sides of the cylinder 267 and extend laterally thereof to their ends which are pivotally mounted in the adjacent plates of the frame 11. The ram 267 accordingly, is adapted to pivot about the common axis of the pins and in the general plane of the upright frame 6.

The plates 162 and 163 of the frame 11 are so arranged in parallel spaced relationship as to be offset outwardly of and above the drilled holes 215 and 257 in the tie when the frame 11 is drawn into pin pressing working position above the end position of the tie to be dowelled. It may be stated at this point that the holes are drilled in the end portion of the tie and the pins are pressed into the holes without changing the resting position of frame 6 on the top of the tie and that when the auxiliary frame is fully drawn rearwardly on the shaft 134 and 135, it arrives at the ram working position with the respective frames abutting one another.

The piston arm end of the ram 267 is provided with a collared L-shaped ram head 277 which opens downwardly and inwardly toward the tie for engaging the upper end of the dowel pin.

The rams 266 and 267 are mounted with their axes parallel to and intermediate the plates 162 and 163 of the frame 11, and although they are not offset to accommodate the offset nature of the axes of the drilled holes 215 and 257, the heads of the rams are nevertheless of sufficient size to engage the ends of the dowel pins when the auxiliary frame is in a working position for the rams. As seen in FIGURE 10, the heads 276 and 277 of the rams 266 and 267 extend laterally of their piston arms 274 and 275 toward the plates 162 and 163. As such, the pin 278 is engaged by the head 277 of ram 276

slightly rearwardly of the axis of piston arm 275, and pin 278 is engaged by head 276 of ram 266 slightly forwardly of the axis of piston arm 274.

The axis of ram 267 is maintained in its generally downwardly and inwardly inclined position by alignment device 269. The device includes a pair of inclined flat plate members 283 and 284 which extend between and are welded to the inside faces of frame plates 162 and 163 and which are offset from and located above the ram cylinder 267. The members are arranged in spaced parallel relationship to each other and are mounted with their planes inclining downwardly and inwardly in parallel directions with the general axis of the ram 267 as shown in FIGURE 4. The plates 283 and 284 are interconnected by a pin 286 which is affixed to the plates 283 and 284 and positioned intermediate of and parallel to the side plates 162 and 163 of the frame 11. The axis of pin 286 is disposed generally normal to the axis of the ram 267 and to the planes of the plates 283 and 284 of the device. An elongated rod element 285 is slidably connected to and extends generally downwardly and inwardly from the pin 286 above the cylinder. The rod 285 is slidably mounted on the pin 286 at its upper end by means of a snugly fitting integrally formed slidable eye component 287 of the rod which because of the snug fit maintains the rod perpendicular to the pin at all times even though it is slidable thereon. The eye component 287 is maintained generally intermediate the plates 283 and 284 by means of a pair of pins surrounding compression springs 288 and 289 which bear outwardly against the adjacent plates 283 and 284 of the device 269 and inwardly against the opposite sides of the rod eye element 287, as shown in FIGURE 9. As such, the springs 288 and 289 constantly urge the eye element 287 of the rod into a position such that the rod 285 axis falls more or less midway between the plates 283 and 284. The lower end of the rod 285 floats between the plates 162 and 163 of the frame 11 and terminates a suitable distance above the bottom of the frame.

The ram head 277 is attached to the device 269 by a suitable arm 281 which, at its upper end, is pivotally mounted, as at 290, to a sleeve 291 which is carried on rod 285. The sleeve is slidably mounted on the rod 285 and adapted to slide back and forth thereon in accord with the movement of piston arm 274. The arm 281 is rigidly welded to the collar 282 of the ram head and is adapted to support the ram 267 through its connection with rod 285 in the inclined general working position shown.

By virtue of the alignment device, the ram head 277 is generally maintained in a pin engaging position and is able to move more or less up and down on its pivotal connection to the frame and thereby adjust itself to the angle with the horizontal which the pin assumes in being pressed into the dowel pin hole in the tie.

The alignment device maintains the head of the ram 267 in a general working position with its axis extending generally in the direction of the drilled hole 215 so that the ram can exert forces on the pin which are substantially in the direction of the hole as the pin is being pressed into the hole. However, when the hole drilled is somewhat off parallel with the general working axis of the ram, as maintained by the alignment device, the device enables the ram to pivot to enable the head to follow the end of the pin as it presses the pin in the hole. Thus, if the pin assumes a position in the hole 215 as it is being pressed into the hole such that the ram head moves in the direction of arrow 301, bar 285 is shoved in the same general direction by arm 281. This causes the bar to slide on pin 286 against the urgings of spring 288. After the pin is pressed fully into the hole and as the ram arm 275 is being retracted, spring 288 urges the rod toward its central position between plates 283 and 284 and this causes the ram head, through the ram

connection with the rod, to be urged back into its general working position again.

It may be stated at this point that the ram is pivotally connected to the plates of frame 11 so that its weight is well balanced on either side of the pivot axis. As such, the weight carried by rod element 285 is small when the ram is held in working position thereby.

THE HYDRAULIC SYSTEM

The hydraulic system for actuating the various hydraulically operated units of the dowelling apparatus is schematically illustrated in FIGURE 8.

Briefly, each hydraulic unit is provided with a feed line and a return line which are controlled in their connections with the pump 26 and the fluid reservoir 300 through a control valve. The feed lines are collectively designated at 301 whereas the return lines are collectively designated at 302.

Pressurized fluid is supplied by the pump 26 to each of the control valves collectively designated at 13 through a pump discharge line 303 and each control valve directs the return fluid from its hydraulically operated unit to the reservoir return line 304 when the unit is hydraulically actuated. Return line 304 discharges the fluid in a tank 300 on the vehicle. The pump draws the fluid to be pressurized from the reservoir 300 through line 305.

The control valves 13 are of a well-known 3-position type. In one position the pressurized fluid from the pump 26 in line 303 is directed into the feed line 301 to the hydraulically actuated unit, and simultaneously the connection between the return line 302 for the unit and the reservoir return line 304 is completed. In the second position the pressurized fluid from the pump discharge line 303 is directed in the return line 302 for the hydraulically actuated unit, and simultaneously the feed line 301 for the unit is connected to the reservoir return line 304. As such, the return and feed lines for the units alternate in their functions as fluid feed and return lines in accord with the positions of their associate control valves. The third position is a neutral position wherein the feed and return lines are disconnected from the pump discharge and reservoir lines 303 and 304 and sealed off from each other, whereby the components of the units are rendered stationary.

The turntable motor 69 is controlled by valve 306. Pinion 72 is caused to rotate in one direction by manually manipulating the lever of valve 306 to the first valve position. This connects the pump discharge line 303 with motor feed line 307 and connects motor return line 308 with reservoir line 304. By manipulating the lever to the second position for the valve 306, the pinion 72 rotates in the opposite direction. This position connects the motor feed line 307 with reservoir return line 304, and connects motor return line 308 with pump discharge line 303. In the third position the feed line 307 and discharge line 308 are disconnected from the reservoir line 304 and pump discharge line 303 and the fluid is sealed in lines 307 and 308 thereby rendering pinion 72 stationary. Drill motors 213 and 213' are similarly controlled.

Control of the hydraulic cylinders of the system is illustrated by reference to the system for the vertical carriage cylinder 113. Cylinder 113 has a feed line 309 and a discharge line 310 which are connected to vertical carriage control valve 311 on opposite sides of the cylinder piston. By manipulating the lever of the control valve 311 to the first position, pressurized fluid is directed into feed line 309 and the piston arm 154 of the hydraulic cylinder 113 is caused to become extended. As the arm 154 becomes extended, the fluid on the arm side of the piston is returned through line 310 and is directed through the control valve 311 into reservoir return line 304. So long as the first position is maintained, the arm 154 is constantly being urged out of the cylinder

by the pressurized fluid. To withdraw the arm 154, the control valve is disposed in the second position, and the pump discharge line 303 is thereby connected to the return line 310 and the feed line 309 is thereby connected to the reservoir return line 304. As such, the piston is forced upwardly and the arm is retracted. The neutral position for control valve 311 disconnects the feed and return lines 309 and 310 from the pump discharge line 303 and line 304 and seals the liquid on the opposite sides of the piston, thus rendering arm 154 stationary.

To shift the carriage assembly from one side of the railway 93 to the other, the vertical carriage 74 is elevated from the position shown in FIGURE 2 by causing the piston arm 154 of hydraulic cylinder 113 to become retracted. This raises the vertical carriage and enables the carriage to be swung over the end portion of the vehicle 1 by properly controlling the actuation of turntable motor 69.

When the frame of the carriage assembly is disposed above the end position of the tie between the adjacent rail and the end of the tie, cylinder 197 of the clamping mechanism 9 is controlled to cause the depending jaw arms to assume a position such that upon lowering the head frame 6 the jaws will straddle the tie to be dowelled and will be forced into the ballast of the road bed on opposite sides of the tie. Thereafter the vertical carriage cylinder 84 is suitably actuated to force the carriage assembly horizontally forward to scoop out the ballast on the opposite sides of the tie to be dowelled. This process is repeated until the sides of the tie are cleared of ballast and the jaws can be effectively caused to clamp the tie without interference from the ballast of the road bed. During the process of clearing the ballast from the sides of the tie, cylinder 197 can be actuated to open the jaws by retracting the arm 202 of cylinder 197. This shoves ballast away from the sides of the tie, and is repeated as necessary to clear the sides of the tie alone or together with forward horizontal movement of the frame 6. During these operations the flanges 208 and 209 function as ballast scoops.

Once the ballast is removed from adjacent the sides of the tie portion to be dowelled, the head frame 6 is caused by suitable control of hydraulic cylinders 84 and 113 to assume a position transversely of the tie with the rest plate 126 positioned inwardly of the end 124 of the tie 122 so as to permit the effective operation of the drilling and ramming mechanisms on the end portion of the tie. The rest plate 126 of the frame is disposed on the crosstie adjacent to the rail plate 94 for supporting rail 95 as shown in FIGURE 2 and positioned rearwardly of the end of the tie.

Thereafter the piston arm 202 of the hydraulic cylinder 197 of the clamping mechanism is extended to force the jaws 200 and 201 into a vise-like crack and split closing 55 clamping grip on the opposite sides of the tie and the grip is maintained throughout the drilling and pin pressing process. This not only closes most of the cracks and splits at the end portion of the tie, but also fixes the frame on the tie so that the heads of the rams will thereafter effectively register with the drilled holes without unnecessary manipulation of auxiliary carriage.

Thereafter, with the auxiliary carriage 75 in its foremost position shown in FIGURE 2, the drill assemblies 210 and 211 are brought into a general working position by controlling hydraulic cylinders 240 and 241 to retract their piston arms. The shoes 223 and 260 of the assemblies are there positioned on the opposite upper side edges of the tie, as shown in FIGURE 3, by suitably controlling cylinders 240 and 241 and shoe adjusting cylinder 236.

When the shoes 223 and 260 are properly adjusted and in position, the valves for the drill motors 213 and 213' are controlled to cause the motors to operate and the hydraulic drill feed cylinders 221 and 221' are controlled to extend their piston arms 225 and 225' thereby forcing 70 the twist drills through their respective openings in the

drill guide shoes and into the tie. Once the generally diagonal and longitudinally offset holes have been drilled, the drill feed cylinders 221 and 221' are controlled to retract their piston arms and to thereby withdraw the tool ends of the drills from the tie.

Following the operation of the drills, the hydraulic cylinders 240 and 241 are controlled to extend their piston arms and thereby swing the drills upwardly and out of position so that the auxiliary frame 11 can be drawn into place.

Frame 11 is then brought rearwardly on the shafts 134 and 135 of the auxiliary carriage 75 and into a position generally beneath the drills 212 and 255 by withdrawing the piston arm 171 of hydraulic carriage cylinder 168.

Thereafter, the operator of the apparatus manually inserts dowel pins between the ram heads 276 and 277 and the respective holes and controls the cylinders 266 and 267 to press the dowel pins into the holes.

Following retraction of the piston arm 274 and 275 of the rams 266 and 267, the pressure on the jaws 200 and 201 is reduced by causing piston arm 202 of floating cylinder 197 to be retracted, and the vertical carriage 74 is elevated by control of cylinder 113. The process is then repeated on the opposite side of the tie by swinging the apparatus to the other side of the vehicle on the turntable.

The dowel pins employed are preferably, as shown in FIGURE 11, of the threaded type commonly employed for dowelling crossties. Such pins have a low pitch screw thread, and thread themselves into the holes as they are being forced thereto without the application of any rotary forces to the pins as they are being forced into the tie.

From the foregoing it can be seen that the apparatus is provided with a means for clamping the tie to close wood separations in the form of cracks and splits at the end portion of the tie to be dowelled, a means for drilling inclined transversely directed holes in the tie, as well as means for pressing the dowel pins into the drilled holes.

While only certain preferred embodiments of this invention have been shown and described by way of illustration, many modifications will occur to those skilled in the art and it is, therefore, desired that it be understood that it is intended in the appended claims to cover all such modifications as fall within the true spirit and scope of this invention.

What is claimed as new and what it is desired to secure by Letters Patent of the United States is:

1. An apparatus for reinforcing a railway crosstie without removing the tie from the road bed of the railway comprising a vehicle, drill means for drilling a hole in the crosstie between one of its ends and the adjacent rail mounted on said tie, and pressing means for pressing a dowel pin into the hole, said drilling means and pressing means being carried by said vehicle.

2. An apparatus in accord with claim 1 further comprising means for clamping the crosstie between said one end and the adjacent rail to close wood separations in said tie.

3. An apparatus for reinforcing a railway crosstie without removing the tie from the road bed, comprising a frame, tie clamping means suspended from said frame for closing wood separations between one end of the tie and the adjacent rail of the railway, a drill connected to said frame and operable to drill a substantially transversely and diagonally inclined hole in said tie, between said end and the adjacent rail, and means for pressing a dowel pin into said hole in said tie, said pressing means being carried by said frame.

4. An apparatus for reinforcing a railway crosstie without removing the tie from the road bed comprising a narrow upright frame adapted to be positioned transversely of and on the upper face of the tie between one of the ends of the tie and the rail adjacent thereto with an end portion of the tie in front of the frame, tie clamping

means suspended beneath said frame for closing wood separations in said end portion, drill means swingably connected to the frame and swingable to a working position in front of said frame from another position remote therefrom for drilling a substantially diagonally inclined and transversely extending hole in the end portion of said tie, and dowel pin pressing means for pressing a dowel pin into said hole, said pressing means being supported by said frame forwardly of said drill working position and being moveable toward the front of said frame into a working position to press a dowel pin into said hole and further moveable away from the front of said frame to a position remote from its working position to thereby enable said drill means to assume its working position between said frame and said pressing means.

5. An apparatus for reinforcing a railway crosstie without removing the tie from the road bed comprising a vehicle for travel on the railway having a turntable mounted thereon, a vertically and horizontally moveable carriage including a narrow upright rigid frame positionable transversely of and on the upper face of the crosstie selectively adjacent to the respective opposite sides of said vehicle with a portion of the tie in front of the frame, a pair of jaw carrying arms suspended dependingly from said frame and arranged to straddle the tie with the jaws adjacent the opposite sides of the tie, means connected to said arms for forcing said jaws into clamping engagement with the sides of said tie, a pair of drills suspended from the frame and swingably disposed in front thereof, said drills being swingable from opposite remote positions adjacent the respective opposite sides of said frame to working positions in which the axes of the drills converge downwardly and inwardly toward the respective opposite upper side edges of said tie, means for swingably connecting said drills to said frame including guide means for guiding the tool ends of the respective drills into the respective side edges of the tie and means for adjusting said guide means on said tie and for swinging said drills to and from their respective working and remote positions, means carried by said swingably connecting means for forcing the drill ends into the tie when the drills are in their respective working positions, an auxiliary frame supported on and moveable toward and away from the front of said rigid frame, means for moving said auxiliary frame toward and away from said rigid frame, a pair of dowel pin rams mounted on said auxiliary frame with their axes converging downwardly and inwardly thereof for pressing dowel pins into the respective holes bored by said drills, said axes being substantially parallel to the axes of the drills when the latter are in their working positions.

6. In an apparatus for reinforcing a railway crosstie without removing the tie from the road bed the combination of a drill, means for positioning said drill in a working position with its axis transversely of and extending substantially diagonally through the tie, means to force the tool end of said drill into said tie along said axis, a ram pivotally mounted in a plane generally in parallel with said axis, and an alignment device connected to said ram for maintaining the axis of the ram generally in parallel with the axis of said drill when in said working position.

7. In an apparatus for reinforcing a railway crosstie without removing the tie from the road bed, the combination of a drill means for selectively positioning said drill at opposite sides of a railway, means for positioning said drill with its axis transverse to and extending substantially diagonally through a crosstie mounted on said selectively positioning means, means carried by said last mentioned means for inserting and withdrawing the tool end of said drill in said tie to obtain a hole therein, and means carried by said selectively positioning means for pressing a dowel pin in said hole.

8. In an apparatus for reinforcing a railway crosstie without removing the tie from the road bed the combination of a drill, a guide for the tool end of said drill, means connected to the guide for positioning the guide on the

19

tie, and means connected to the drill and to said positioning means for forcing the tool end of the drill along an axis which extends transversely to and substantially diagonally through the tie.

9. In an apparatus for reinforcing a railway crosstie without removing the tie from the road bed, the combination of a rigid frame, an auxiliary frame mounted on and moveable toward and away from the rigid frame, a drill suspended from the rigid frame for drilling a hole in a crosstie at a working position disposed between said frames, means for moving said drill from between said

5

10

20

frames to a position remote thereto, dowel pin pressing means mounted on the auxiliary frame for pressing a dowel pin in the hole, and means for moving said frames toward and away from each other.
